(57) **CLAIM**

I claim the ornamental design for an automobile window shade, as shown and described.

DESCRIPTION

FIG. 1 is a front view of the automobile window shade wherein the cross-hatch shading represents a surface colored black.

FIG. 2 is a rear view of the automobile window shade wherein the shading represents a reflective silver surface.

FIG. 3 is a right side view of the automobile window shade.

FIG. 4 is a left side view of the automobile window shade.

FIG. 5 is a bottom view of the automobile window shade; and,

FIG. 6 is a top view of the automobile window shade.

The broken lines in FIGS. 1 and 2 are seams.

The shading in the Figures depict the colors black and silver.
